G. G. FLOYD

CONTAINER

Original Filed July 23, 1924

UNITED STATES PATENT OFFICE.

GEORGE G. FLOYD, OF RIVERSIDE, ILLINOIS.

CONTAINER.

Original application filed July 23, 1924, Serial No. 727,634. Divided and this application filed November 19, 1925. Serial No. 70,109.

My invention relates to containers or receptacles for use in fountain brushes which contain a supply of material, such as shaving-cream, and which may be forced a little at a time into the bristles of the brush for lathering or similar purposes, and, although the invention is illustrated and described in connection with brushes particularly suited for lathering preliminary to shaving, the new container is not restricted to any particular art or use because its principles of construction and method of functioning adapt it for satisfactory employment in other relations.

One aim of the invention is to provide a tube or cartridge having such characteristics that it may be used in a fountain brush with ease and facility and when its supply of shaving-cream, soap or the like has become exhausted, such container may be replaced by the insertion of another full one in the brush.

Another aim of the invention is to provide a container or cartridge of this type wherein the contents of the same may be easily expelled in small quantities, as may be required in the use of the associated brush.

This application is a division of my earlier application, Serial No. 727,634, for fountain lather brushes, filed July 23rd, 1924.

To enable those skilled in this art to have a full and complete understanding of the invention both from structural and functional standpoints, in the accompanying drawing forming a part of this specification and throughout the several views of which like reference characters have been employed to designate the same parts, I have illustrated a desirable and preferred embodiment of the invention and in order that its manner of use may be fully comprehended, the fountain brush in which it is intended to be employed has been illustrated and described in more or less detail.

In this drawing:

Figure 1 is an elevation of the brush housing the new style of container or cartridge.

Figure 2 is an elevation of one of such tubes or cartridges containing the shaving-cream or soap adapted to be used in the handle of the brush;

Figure 3 is an enlarged longitudinal section through the brush showing the cartridge or container in position therein;

Figure 4 is a cross-section on line 4—4 of 55
Figure 3 on a reduced scale;

Figure 5 is a cross-section on line 5—5 of
Figure 3 on a similar scale;

Figure 6 is a cross-section on line 6—6 of
Figure 3 also on a reduced scale; 60

Figure 7 is a similar cross-section on the
broken line 7—7 of Figure 3 likewise on a
reduced scale; and

Figure 8 is a face view of the expandable
and contractible nut used in the handle of 65
the brush for expelling the contents of the
tube or cartridge.

The brush, as is fully shown in the several views of the drawing, includes a main, 70
cylindrical, metal shell or casing 11 internally screw-threaded at one end, that is the brush end of the appliance, at 12 and equipped with an inturned flange or rim 13 at its opposite end.

This casing or shell constitutes the main 75
body or handle of the brush which is
designed to accommodate or house the
removable tube or cartridge of shaving-
cream or soap, characterized as a whole 14,
and constituting the subject-matter of the 80
present invention.

A round brush-holder 15 of appropriate
design has a threaded inner end 16 screwed
into the part 12 of the external shell or cas- 85
ing 11, the outer portion of the holder hav-
ing a cylindrical recess or cavity 17 fric-
tionally, but removably, holding therein the
hollow head portion 18 of an appropriate
brush 19.

Member 15 has a central, hollow, cylind- 90
rical stem or pipe 21 apertured at its end
at 22 to form a valve port and projecting
well into the bristles of the brush, the ele-
ment 18 being shaped for the extension of
the stem or pipe 21 therethrough as is fully
shown in Figure 3.

On its inner face, the member 15 has a
central, externally-threaded, boss 23 fitting
in a corresponding, complementary, inter-
nally-threaded socket 24 on the center of one
end of the cylindrical cream or soap tube or
cartridge 14 which is conveniently made of
thin metal, such as the well-known collaps-
ible dental and shaving-cream tubes. 100

A long, hollow, externally-threaded rod 105
or shaft 25 is positioned centrally within the
cream tube or cartridge 14 and extends sub-
stantially the whole length of the latter.

Such shaft or rod at one end has a head comprising a circular flange portion 26 inside of shell or casing 11 and bearing on the inner face of flange 13 and a flat, handle part 27 extended out through the end opening of the element 11 and by which means the screw-threaded rod or shaft may be manually turned.

A long plunger or valve stem 28 is slidingly accommodated in the bore of rod 25 and at one end in the tubular member 21 has a head 29 of substantially the diameter of the hollow interior of such member to form a cream-expelling or discharging piston and a valve for opening and closing the port 22.

The other end of the rod or valve stem 28 is fixed or secured to a cap 31 normally covering the flat handle 27, as shown in Figure 3, but of course capable of sliding movement to effect corresponding action of the plunger or valve rod 28.

The cream or soap tube or cartridge 14 at one end has a follower 32 with a thin cylindrical wall 33 inside of the tube or cartridge and of an outside diameter slightly greater than the internal diameter of the tube, whereby a snug and non-leaking joint is maintained with the tube, such follower having an external, central, boss 34 with screw-threads 35 on its outside and with a central, hexagonal cavity 36 designed to receive the divided, hexagonal part 37, 37 of a split-nut 38, 38 which is internally threaded to fit the rod or shaft 25.

The companion parts 38, 38 of the nut are each pivoted to a common, suitably-shaped plate 39 at 41, 41, such plate or support having a central hole 42 therethrough of larger diameter than the threads of rod 25 so as to be freely slideable thereover.

To limit or restrict the opening movements of the complementary nut sections 38, 38, each is conveniently supplied with a stop-pin 43 projecting into a recess 44 of the plate 39, the pin by engagement with an end wall of such recess acting as a stop or abutment to limit the opening or expanding movements, as shown in Figure 8.

At its other or inner end, the hollow, screw rod 25 is fitted with a washer or collar slightly larger in diameter than that of the hole 42 of plate 39, whereby the split-nut cannot be removed from the rod.

When the valve-stem 28 is withdrawn to its full extent, the valve or piston 29 will occupy the position shown in dotted lines in Figure 3 and in order that the semi-liquid contents of the tube may have access to the discharge conduit in pipe 21, that part 45 of lug 23 beyond its threaded portion is longitudinally slotted at 46.

In actual practice, it has been found to be convenient to make the collapsible supply

tube or cartridge and its follower of pure tin with their cylindrical walls of approximately seven one-thousandths of an inch in thickness and in order that the friction between the telescoping walls of such tube and follower may be supplemented by appropriate means to insure that the follower will not turn in the tube, it is provided with a slight outward projection at the point 51 causing a corresponding slight projection in the outer tube at the same point.

The operation of the appliance is substantially as follows. Assuming that the parts of the structure are as indicated in Figure 3 and that it is desired to project a small charge of shaving soap or cream from the container or tube into the brush for working up into a lather, the operator first pulls out or retracts the united cover 31 and the valve stem and valve 28, 29 into the dotted line position uncovering the slots 46.

Then the handle 27 is given a proper amount of turning to feed the nut 37, 37 inwardly slightly which pushes the follower 32 ahead of it in the stationary cartridge, thus expelling a portion of its semi-fluid contents into the pipe or tube 21 and possibly some through the valve port 22 into the brush bristles.

During this slight lengthwise travel of the follower, it is prevented from turning in the tube or cartridge because of its frictional fit in the latter and because of the interfitting indentations 51.

Owing to the hexagonal shape of the interlocking parts of the follower and nut, the latter is also prevented from rotation which occasions its longitudinal travel during the angular movement of the handle and its threaded rod 25 over which the nut fits.

Then the cover 31 and the valve 29 and its stem 28 are pushed fully in into the full line positions shown in Figure 3, the valve or piston 29 forcing the contents of tube 21 out through the valve port 22 into the brush whereby there is no small body of soap or cream left in the brush handle and associated parts which would be likely to harden and to render the operation of the device difficult or uncertain.

The brush having been thus charged with soap or cream, it is ready for use in the usual manner.

Due to the fact that the follower is filled with cream or soap, it maintains its full size during successive, progressive, inward movements, and constitutes an effective cream or soap expulsion plunger or piston.

Because it is slightly larger than the tube proper, it maintains its tight fit therewith and in very small degree expands the tube as it progresses inwardly.

When it reaches the inner end of the tube

or cartridge, it collapses under the pressure exerted and thus permits a complete discharge or delivery of the tube contents.

Assuming now that it is desired to remove 5 the emptied tube and to replace it with a new filled one, we proceed as follows, understanding that such tube has been emptied by successive movements of the parts as indicated above.

10 The hollow handle casing or shell 11 is unscrewed from the brush-holder 15 and removed longitudinally from the structure carrying with it the parts 27, 25, 28, 29 and the split nut 37, 37, whereupon the emptied 15 or exhausted tube and its collapsed follower may be unscrewed from the member 15 and thrown away.

20 The screw rod or shaft 25 and associated elements having been removed from the handle, the divided or split nut is then opened up or expanded and quickly slid down to the other end of the hollow, threaded rod 25, thus avoiding the necessity of slowly screwing it down into place, and in 25 its new position it is again contracted on to the threads of the rod 25 ready for use.

Each new filled tube 14, see Figure 2, before it is inserted in the brush-handle, has a closure 52 screwed into the tube socket 30 24 and at its other end the tube has a cap 24 53 screwed on to the threaded end 34, whereby the contents of the tube are always maintained in fresh and proper condition and the tube is kept from losing any of its soap or 35 cream.

In other words, these two elements 52 and 53 comprise temporary stoppers or closures for the two ends of the cartridge until the latter is ready for employment 40 in the brush-handle, when they are taken off.

Then the united threaded rod 25, valve 29 and its valve stem 28 are pushed through 45 the pair of aligned holes at the two ends of the new, filled tube, the closures 52 and 53 having been previously removed, and the hexagonal socket 36 is easily fitted over the correspondingly shaped part of the nut 37, 37, as is clearly shown in Figure 3.

50 Then the threaded boss 23 of the member 15 is screwed into the corresponding end of the tube, the stem 28 and valve 29 acting as a centering guide, whereupon the handle casing 11 is applied and screwed on to the 55 brush-holder 15.

The brush is now ready for use as explained above with the gradual, progressive, manual travel of the nut and follower inwardly to press or force out the contents of 60 the tube, which action is supplemented by that of the reciprocatory plunger and valve 29.

It will be observed that the part 31, when 65 in the position shown in Figure 3, forms a cover for the flat handle 27. So far as the

brush is concerned, this is a feature of importance, because it requires the retraction of the element 31, thus effecting the opening of the discharge valve-port 22, before the tube-follower can be advanced by the 70 turning of handle 27 to deliver a portion of the soft contents. If the valve-port remained closed and the handle 27 were turned a substantial amount, there would be a tendency to burst or rupture the soft, 75 thin-metal tube, due to the fact that its soap or cream could not find other egress under the exerted pressure.

If the operator should fail to push the cover 31 in after it has been retracted, this 80 is accomplished more or less automatically when he sets the brush up on its end, which action would naturally result, either by pressure exerted by the operator or by the weight of the parts, in carrying the brush 85 handle and associated parts down sufficiently to push in the valve and its stem cover 31 fully home.

Those skilled in this art will readily understand that this invention is not limited 90 and restricted to the precise and exact structural features presented, and that many minor mechanical changes may be made in the new tube or cartridge illustrated and described without departure from the 95 heart and essence of the invention and without the sacrifice of any of its substantial benefits and advantages.

I claim:

1. A supply-tube adapted to contain semi-fluid material having a follower closing one end thereof and slideable in the tube to expel the contents of the latter, said tube and follower being apertured in register, and removable means to close said apertures temporarily until the tube is to be put into use. 100

2. An apertured cylindrical supply-tube made of thin collapsible metal having therein a cylindrical slideable follower to expel the contents of the tube and of an external 110 diameter slightly greater than the internal diameter of that part of the tube ahead of it.

3. An apertured cylindrical thin collapsible-metal supply-tube having a cylindrical follower closing one end of the tube 115 and slideable therein to expel the contents of the tube and also made of thin collapsible metal, and means to prevent said follower from turning in the tube.

4. An apertured thin collapsible-metal cylindrical supply-tube having a cylindrical flanged follower slideable therein to expel the contents of the tube and also made of thin collapsible metal, said follower being of an external diameter slightly greater than the internal diameter of the tube whereby to expand the latter in small degree during its lengthwise travel therein to maintain a tight fit therewith. 120

5. An apertured thin collapsible metal cy- 130

lindrical supply-tube having a cylindrical flanged follower slidable therein to expel the contents of the tube, said tube and follower being apertured in register, said 5 follower being of an external diameter slightly greater than the internal diameter of the tube whereby to expand the latter in small degree during its travel lengthwise therein to maintain a tight fit therewith, 10 and removable means to close the apertures of said tube and follower temporarily.

6. An apertured cylindrical supply-tube

made of thin collapsible-metal having a cy-
lindrical thin collapsible-metal follower slid-
able therein to expel the contents of the 15
tube, such follower having a collapsible-
metal flange on its inner surface of an ex-
ternal diameter slightly greater than the in-
ternal diameter of that part of the tube
ahead of it. 20

In witness whereof I have hereunto set
my hand.

GEORGE G. FLOYD.
